CLAIM

The ornamental design for a TV receiver, as shown and described.

DESCRIPTION

1. TV receiver
- 1.1 : Perspective
- 1.2 : Front
- 1.3 : Back
- 1.4 : Left
- 1.5 : Right
- 1.6 : Top
- 1.7 : Bottom

(Continued)

The broken lines in figures 1.3- 1.5 and 1.7 showing the three panels on the back of the TV receiver as well as the curved broken lines shown in figure 1.7 are included for the purpose of illustrating portions of the article and form no part of the claimed design.

1 Claim, 4 Drawing Sheets
